US0D1040512S

(12) **United States Design Patent** (10) **Patent No.:** **US D1,040,512 S**
(45) **Date of Patent:** **** Sep. 3, 2024**

(54) **COVER FOR ELECTRONIC DEVICE**

(71) Applicant: **ELAGO CO. LTD**, Goyang-si (KR)

(72) Inventor: **Chanwoo Lee**, Goyang-si (KR)

(73) Assignee: **ELAGO CO. LTD**, Goyang-si (KR)

(**) Term: **15 Years**

(21) Appl. No.: **29/927,053**

(22) Filed: **Feb. 2, 2024**

(51) **LOC (14) Cl.** **03-01**

(52) **U.S. Cl.**

(57) **CLAIM**

The ornamental design for a cover for electronic device, as shown and described.

DESCRIPTION

FIG. 1 is a front, top, and right side perspective view of a cover for electronic device, showing my new design; FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a back, top, and left side perspective view of the cover for electronic device; and, FIG. 9 is a back, bottom, and right side perspective view of the cover for electronic device.

The broken lines and the unshaded areas within them depict interior parts of the cover for electronic device that form no part of the claimed design.

1 Claim, 7 Drawing Sheets
